UNITED STATES PATENT OFFICE.

JAMES C. WOODSON, OF MANSFIELD, OHIO, ASSIGNOR TO WESTINGHOUSE ELECTRIC & MANUFACTURING COMPANY, A CORPORATION OF PENNSYLVANIA.

ELECTRICALLY-HEATED OVEN.

Application filed December 13, 1927. Serial No. 239,662.

My invention relates to electrically heated ovens and more particularly to means for removably mounting heating elements therein.

An object of my invention is to provide 5 an improved means for mounting a plurality of electric heating elements in an electric oven whereby the insertion or the removal thereof, as a unit, into or from the oven chamber is permitted.

10 Another object of my invention is to provide, in an electric oven, a combined shelf-support and heating-element mounting, and removable means for securing said structure in operative position in the oven chamber.

15 A further object of my invention is to provide an improved means for making the electric circuit connections for a plurality of electric heating elements which are removably mounted in an oven chamber.

20 In practicing my invention, I provide, in conjunction with an oven chamber, a skeleton frame extending over the floor and side walls thereof, a plurality of shelf-supporting brackets and heating elements secured thereto, and electric contact means, carried by said frame, adapted to cooperate with contact means mounted upon an adjacent furnace wall to energize said elements only when said frame is in operative position.

25 30 In the drawings, Figure 1 is a view, in front elevation, of an oven embodying my invention, the door thereof being in an open position and partially broken away.

Fig. 2 is a vertical section taken on line II-II of Fig. 1.

35 Fig. 3 is a view, in perspective, of the heating-element supporting structure removed from the furnace chamber.

Referring more particularly to the drawings, an oven 2, embodying my invention, comprises a floor, roof, and plurality of side walls defining a substantially rectangular furnace chamber 4. The floor, roof, and side walls are constructed of parallel-extending sheets of metal having a suitable heat-insulating refractory packing substantially filling the space therebetween. The elements are maintained in operative relation by vertically extending angle irons 8 which project below the level of the oven floor and constitute a support for the oven.

40 45 50 The front wall of the oven is hinged to one of the vertical angle irons 8 to constitute a door for facilitating the charging and removal of material with respect to the oven.

chamber 4. The door is substantially coextensive, in height and width, with the lateral dimensions of the furnace chamber, so that, with the door in the open position thereof, the entire interior of the oven chamber is exposed.

55 A combined shelf and resistor-supporting frame 10 is located in the oven chamber, and comprises vertically extending angle irons 12 and 14, substantially coextensive with the height of the oven chamber side walls, and a base frame 16, secured to the angles 12 and 14 a short distance above the lower extremities thereof. The upper extremities of the angle irons 12 and 14 are connected by angles 18 and 20, respectively, each having a horizontal flange extending inwardly from the faces of the vertically extending angle irons 12 and 14.

60 65 70 The arrangement is such that the angle irons 18 and 20 may be moved apart a limited distance, for a purpose hereinafter described.

75 A plurality of vertically spaced bayonet slots 22 are provided in the angle irons 12 and 14 and are adapted to be engaged, selectively, by suitable pins mounted upon shelf-supporting brackets 24. The number of pairs of brackets employed, or the relative positions thereof, may be varied, according to 80 the number and arrangement of work-supporting shelves employed. A showing of the shelves has been omitted from the drawing, but it is to be understood that they are of the usual sheet-metal construction.

85 90 95 Heating elements 26, of the encased resistance type, are secured to the side and base frames, as indicated more particularly in Fig. 3, and the terminals thereof are electrically connected, respectively, to bus bars 28 and 30.

100 105 The bus bar 28 extends along the front angle irons 12 and 14 and beneath the front edge of the base frame 16. The bus bar 30 cooperates with the rear angle irons 12 and 14 and the rear edge of the base frame in a similar manner. The portion thereof extending under the rear edge of the base frame is broken, however, and the ends thereof connected to a double contact plug, shown diagrammatically only, which is adapted to cooperate with a socket 32, mounted in the oven rear wall, to complete a circuit through the heating elements.

110 When the heating elements have been

mounted upon the frame, and the necessary electrical connections completed, the structure may be moved, as a unit, into the furnace chamber. With the structure in position in the furnace chamber, the vertically and horizontally extending portions thereof are adjacent to the side walls and floor, respectively, of the furnace chamber and are substantially coextensive in area therewith. The structure is then secured in operative position by a wedging frame 34, which is forced into position upon the horizontal flanges of the angle irons 18 and 20. The lateral dimensions of the frame 34 are such that, when it is forced into position, it tends to spread the angle irons 18 and 20 laterally, and to force, thereby, the angle irons 12 and 14 against the side walls of the oven chamber. A desired number of shelves are then positioned upon the supporting brackets 24 and the oven is ready for operation.

By my invention, I have provided an improved structure for mounting electrical heating elements and shelf-supporting brackets in an electrical heating furnace, whereby the structure and heating elements may be moved, as a unit, into or out of an oven chamber and may be removably secured therein. Also by my invention, all electrical connections of the heaters may be effected outside of the oven, and the heaters are prevented from being energized until the supporting structure is in operative position within the oven. Further, since the heating elements and electrical connections therefor are disposed in the recess defined by the angle irons 12 and 14, the elements are maintained out of contact with the work being heated and the side walls of the oven.

Quite clearly, many changes may be made in the structure details disclosed without departing from the spirit of the invention. For example, the oven structure and shape may be varied within wide limits, and electrical heating elements of various types may be employed.

Various modifications may be made, in my invention, without departing from the spirit and scope thereof, and I desire, therefore, that only such limitations shall be placed thereon as imposed by the prior art and set forth in the appended claims.

I claim as my invention:

1. In an electric oven, means forming a combined shelf-support and heating-element mounting comprising a skeleton frame extending over the bottom and side walls of the oven chamber, and means for securing said

frame in operative position in said chamber comprising means for spreading the side-wall portions thereof into engagement with the adjacent oven side walls.

2. In an electric oven, a skeleton frame substantially covering the floor and a pair of opposed side walls of the heating chamber thereof, means cooperating with the side-wall portions of said frame for removably securing said frame in said chamber and means for mounting a plurality of electric heating elements on said frame.

3. In an electric oven, the combination with a heating chamber and a plurality of electric heating units, of means for supporting said heating units comprising a frame substantially coextensive with the bottom and side walls of said chamber, means for removably securing said frame in operative position within said chamber, and cooperating means on said frame and a wall of said oven for completing an electric circuit to said heating units.

4. In an electric oven, the combination with a heating chamber and a plurality of resistor elements for effecting the heating thereof, of means for mounting said elements as a unitary removable structure, comprising a skeleton frame substantially coextensive in dimensions with the floor and side walls of said chamber, means for mounting said elements thereon, and means for releasably securing said frame in said chamber.

5. In a combined shelf-support and heating-element mounting for an electric oven, a skeleton frame including a base substantially coextensive in area with the area of the floor of said oven and vertically extending portions adapted to extend over the side walls thereof, a plurality of shelf-supporting brackets adjustably mounted upon said frame, means for mounting a plurality of heating elements upon said frame, and means cooperating with the vertically extending portions of said frame for removably securing said frame in said oven.

6. In an electric oven, a frame therein substantially coextensive in over-all dimensions with the chamber of said oven, a plurality of heating elements secured thereto, means for securing said frame in operative position within said oven chamber, and means permitting the removal of said frame and elements, as a unit, from said oven.

In testimony whereof, I have hereunto subscribed my name this 2nd day of December, 1927.

JAMES C. WOODSON.
